United States Patent Office

Des. 186,585
Patented Nov. 10, 1959

186,585

MAT

Whitman Byers, Jr., Washington, D.C.
Application July 17, 1959, Serial No. 56,820

Term of patent 14 years

(Cl. D9—6)

Fig. 1 is a plan view of a mat, showing my invention.

Fig. 2 is a sectional view taken substantially along the line 2—2 of Fig. 1.

Fig. 3 is a sectional view taken substantially along the line 3—3 of Fig. 1.

I claim:

The ornamental design for a mat, as shown.
